(57)

CLAIM

The ornamental design for a bike rack, as shown and described.

DESCRIPTION

FIG. 1 is a front right perspective view from above of a bike rack according to the new design;

FIG. 2 is a rear left perspective view from below thereof;

FIG. 3 is a front elevational view thereof;

FIG. 4 is a right side elevational view thereof;

FIG. 5 is a left side elevational view thereof;

FIG. 6 is a rear elevational view thereof;

FIG. 7 is a top view thereof; and,

FIG. 8 is a bottom view thereof.

The broken lines in the drawings illustrate portions of the bike rack and form no part of the claimed design.

1 Claim, 6 Drawing Sheets
